Patented Aug. 10, 1915.

UNITED STATES PATENT OFFICE.

PATRICK F. MORRISSEY AND HERMAN W. TRAUB, OF AUBURN, NEW YORK.

PORTABLE FIRE-ESCAPE.

1,149,394.

Specification of Letters Patent. Patented Aug. 10, 1915.

Application filed August 9, 1913, Serial No. 783,951. Renewed January 30, 1915. Serial No. 5,308.

To all whom it may concern:

Be it known that we, PATRICK F. MORRISSEY and HERMAN W. TRAUB, citizens of the United States of America, residing at

5 Auburn, in the county of Cayuga and State of New York, have invented certain new and useful Improvements in Portable Fire-Escapes, of which the following is a specification.

10 The invention relates to a portable fire escape of the friction controlled type, wherein in the fire escape is designed for travel lengthwise the supporting rope or cable, with its speed of travel governed by a manually operated friction element or brake.

15 The main object of the present invention is the provision of a portable fire escape of simple construction, which may be readily and conveniently connected to or disconnected from the supporting cable and in which the friction brake element is so arranged as to permit the operator to govern the speed of descent with certainty and without liability of injury.

20 25 A further object of the invention is the provision of means whereby the brake element may be set for a predetermined pressure to regulate the descent of the fire escape without requiring particular attention on the part of the user.

30 The invention in its preferred form of details will be described in the following specification, reference being had particularly to the accompanying drawings, in

35 which:—

Figure 1 is a perspective view of the improved fire escape, showing the same in position on a supporting cable, and connected to a life belt. Fig. 2 is an enlarged rear elevation of the same, the cable and belt being omitted. Fig. 3 is a vertical central section of the same. Fig. 4 is a rear elevation. Fig. 5 is a perspective of a slightly modified construction. Fig. 6 is a broken

45 perspective illustrating a means for securing the friction brake in set position.

40 In the preferred type of fire escape, as illustrated in Figs. 1, 2 and 3, the improved structure comprises a main plate 1 preferably of an elongated type and of such material and size as will support the maximum weight for which the fire escape is designed. The upper end of the plate is provided with a snap hook 2, of elongated form with the bill thereof comparatively long and the movable section breaking the hook about one

half the length of one side, so that the upper end of the hook is of solid construction. The lower end of the plate 1 is provided with a ring 3 designed to be secured to a life belt 4 through the medium of a strap element 5, as shown in Fig. 1, whereby the fire escape proper is more or less permanently secured to the life belt.

45 The plate 1 immediately below the snap hook is formed with a transverse recess 6, said recess opening through one edge of the plate, as shown. The edges of the recess are preferably rounded to avoid wear upon the supporting cable, the recess being of course 70 of a width to permit a cable of the maximum size contemplated to pass freely therethrough.

50 55 The friction brake element 7 is secured to the main plate 1 being pivotally connected 75 at 8 to said plate intermediate the snap hook and recess 6. The brake element, which is approximately of the length and width of the main plate 1, is of concavo-convex shape in cross section and is terminally formed 80 at its lower or free end with an outstanding projection or lip 9 to prevent the operator's hand from slipping off said element in the use of the latter to govern the descent of the fire escape. That edge of the brake element 85 overlying the entrance to the recess 6 is formed with an outstanding lug 10, which in all operative positions of the brake element is adapted to close said recess, so that when the parts are in operative position 90 on the supporting cable, the recess becomes in fact merely a hole in the main plate from the standpoint of positively preventing the separation of the cable therefrom.

95 100 In the form shown in Figs. 4 and 5, the cable receiving element at the upper end of the main plate is merely an open ring 11, while the ring 3 at the lower end of the main plate is, in this form, shown connected with a suspension loop 12 in which the operator is adapted to sit.

105 In Fig. 6, we have shown a means for locking the friction brake so that it may be set to maintain a certain pressure upon the cable in order to regulate the descent of the fire escape as desired, it being obvious that the locking means may be adjusted during the descent to vary the speed thereof, though under other circumstances the locking means 110 requires no attention on the part of the operator in its initial setting. In provid-

ing for this securing means we arrange arms 15 at opposite edges of the brake element 7 near the handle end thereof, the arms projecting toward, and passing on opposite 5 sides of and beyond the main plate 1. Pivotally connected to one of the arms is a cross bar 16, the free end of the bar being adapted for removable connection by a pin 17 or the like with the other arm. The cross bar 16 is 10 centrally formed with an opening 18 interiorly threaded to receive a pressure rod or stud 19, the inner end of which bears against the main plate and the outer or free end of which is provided with a handle 20. By adjusting the pressure stud prior to or during 15 the descent of the fire escape it is obvious that any desired pressure may be applied to the friction brake and that the descent of the fire escape may be thus regulated in a simple 20 and more expeditious manner, particularly when in use by inexperienced persons, than as it is by the direct pressure of the hand upon the friction brake.

In use, the supporting cable 13, the upper end 14 of which is secured to a suitable fixture, is placed in coöperation with the fire escape by passing the cable into the snap hook 2, or ring 11, as the case may be, and taking one or more turns of the cable about 25 the hook or ring, as shown. The cable is then passed downwardly in rear of the main plate 1, laterally into the recess 6, and depends from said recess in juxtaposition to the front or forward face of the main plate 30 directly beneath the friction brake element 7.

The operator about whom the life belt is secured or who is seated in the supporting loop 12, readily controls the speed of travel 35 of the fire escape down the cable by exerting the appropriate pressure upon the brake element 7, the hand operating the element grasping said element and main plate in an obvious manner.

As previously stated, the lug 10 on the 40 friction brake element serves to prevent

escape of the cable from the recess 6 while the device is in use, though it is perfectly obvious that by elevating the friction brake element the fire escape may be readily and quickly separated from the cable.

50

The coils of the cable about the upper ring or snap hook serve to assist in retarding the descent of the fire escape on the cable, while the concavo-convex formation of the friction brake element will serve to prevent possibility of the hand of the operator coming in contact with the cable during operation.

55

The fire escape proper is constructed entirely of metal, is so small and light that it may be conveniently transported in a suitcase, or even in the pocket, and may be readily and quickly applied to any size or type of cable without experience and without the necessity of complicated manipulation.

60

What is claimed is:—

1. A fire escape including a main plate, a snap hook at one end thereof, a ring at the opposite end thereof, a recess formed in and opening through one edge of the plate, 70 and a brake element pivotally connected to and overlying the main plate, said element having a lug to close the open end of the recess in all operative positions of the element.

75

2. A fire escape including a main plate, a friction element coöperteing therewith, and a ring member carried by said plate, said member having an entrance opening and being of a size to permit the cable to be 80 introduced therein and coiled one or more times about the perimeter thereof.

85

In testimony whereof we affix our signatures in presence of two witnesses.

PATRICK F. MORRISSEY.
HERMAN W. TRAUB.
